E. I. du Pont de Nemours & Company, Wil-
mington, Del., a corporation of Delaware

Application April 5, 1937, Serial No. 135,064

4 Claims. (Cl. 206—46)

This invention relates to the packaging of materials in the wet state. More particularly, it relates to the packaging of cellulosic structures in the gel state.

5 Hollow pellicular structures in the form of bands or caps designed as secondary closures for bottles are produced in a highly hydrated gel state which, upon drying and subsequent loss of moisture, will shrink considerably, forming a tight 10 skin upon the neck of the bottle and the cap or cork used as a primary closure, which skin conforms closely to the contour of the surface to which it is applied. These pellicular structures, from the time that they are manufactured to the 15 time that they are applied to bottles, must be prevented from drying out and losing their moisture content. Prior to this invention, it was the practice of the manufacturers of such pellicles to store and to ship said pellicles immersed in a 20 suitable solution in a liquid tight container. This solution contained generally a softener such as glycerol in a suitable concentration to give the pellicular structures immersed therein the necessary characteristics of pliability and shrinkage. 25 In addition, certain preservatives and mold inhibitors were incorporated in the solution. Such solutions were relatively expensive and large quantities were disposed of by the customer after the caps or bands had been used. Furthermore, 30 a relatively large amount of solution was required to protect the bands in transit and therefore entailed an excessive freight charge upon the package.

In order to economize upon the use of solution 35 and reduce shipping charges, it has been suggested to thoroughly impregnate the pellicular structures with a suitable solution and then drain off the excess liquor. The structures, thus drained, are then placed in large containers with 40 a volume of about $\frac{3}{4}$ of a cubic foot and hermetically sealed. This method is enhanced by the use of a rubber lining within the container. In many cases, however, particularly where long 45 periods of time have elapsed, users have experienced great difficulty in handling the pellicles.

It is therefore an object of this invention to provide a means for the shipment and storage of material in wet condition.

It is a further object of this invention to provide means for the shipment and storage of pellicular structures in the gel state.

It is a still further object to provide a method for the storage of such structures over an indefinite period of time without any impairment in ease and convenience of handling.

It is a still further object to maintain a film of liquid on stored pellicles over long periods of time.

Still another object is the provision of such shipping and storage facilities without the use 5 of a large excess of liquid.

A still further object is the production of a package of such structures containing units which shall be conveniently handled.

Other objects will appear hereinafter.

In general, these objects are accomplished by providing shallow, waterproof trays for each layer of such structures, which structures are packed in a vertical position so that one edge is in contact with the floor of the tray, and providing a hermetically sealed container for a stack of such trays.

Figure 1 is a partly sectional elevation of a packed metal container. Figure 2 is a partly 20 sectional elevation of a tray and its contents.

When gel pellicles are stored for a period much longer than two or three days (and this is often necessitated by the operational schedule of the consumer), it is found that the film of moisture adhering to the surface of the structures has a 25 tendency to drain off from the material in the upper portion of the package although there is no actual drying or loss of moisture from the gel structure. The loss of the film of liquid from the surface has been found to be a very serious 30 disadvantage in the application of the bands or caps to bottles. These tubular structures are packed and shipped in a flattened condition. It has been found that with the loss of the liquid film, the inner surfaces tend to stick together 35 and to require such a lengthy time of manipulation as to make their use impracticable in the bottling operation of the consumer. When, on the other hand, the surface is provided with a film of liquid, these articles are very readily 40 manipulated on to the bottles or other containers on which they serve as secondary closures. It is impracticable to again wet the structures, once they have lost this film of liquid. In the first place, pure water cannot be used for the wetting since it would remove part of the softener 45 and the preservative which is essential, and secondly, liquid could not be made to penetrate the inner surfaces without manipulation.

Referring now to the drawing, Figure 1 depicts 50 a preferred embodiment of the invention. In this figure, 1 is a cylindrical, straight walled, metal container which has as a liner a rubber bag 5. Within the rubber bag is a series of trays 6, each packed with band structures 7 arranged 55

in a vertical position so that one open edge is in contact with the floor of the tray. The construction of the tray itself and its contents is shown more clearly in Figure 2. Trays may be packed outside of the container and then inserted, or a tray may be introduced into the container and then packed with bands in a given, orderly arrangement, other trays being introduced and packed until the container is filled. As each tray is packed, a small amount of solution is added if necessary to insure the presence of a thin layer 8, perhaps $\frac{1}{8}$ " deep in the bottom of the tray. The addition of solution may not be necessary if the bands being packed into the trays are in a dripping condition. It is only essential that an excess of liquid be present in contact with the bands and it is unimportant whether it be originally associated with the bands or later added.

When the container is completely packed, the top of the rubber liner, when one is used, is folded over and closed by means of a rubber band 9 or other suitable device and a lid attached to the metal container, giving both protection to the contents and a hermetical seal to the container.

25 The trays or separators used in this package perform a dual function: firstly, they preserve the orderly arrangement of bands in the package during handling and unpacking, serving also as a convenient means for removing and handling small units or groups of bands; secondly, because of their waterproof nature, they prevent the draining away of solutions from the upper layers of bands, thus maintaining a small amount of liquid associated with each layer of bands. Where 30 these pellicular structures are to be stored for a relatively long period of time, it is necessary that the trays be made of highly waterproof material which is unaffected by the particular solution employed. Trays made of a stiff paper 35 impregnated with linseed oil are highly satisfactory in this connection and quite inexpensive.

It is not necessary that the walls of the trays have a depth as great as the length of bands being packed. It is only necessary that this depth 40 be equal to or greater than the depth of liquid which it is desired to keep in contact with the bands. It is preferable, of course, that the depth of tray be in excess of the depth of liquid desired, so that tilting of the container will not cause an 45 undue discharge of liquid from the upper trays to the lower. A depth of 1", for example, operates satisfactorily and is applicable to a variety of band sizes.

50 It is necessary that the container be hermetically sealed and provide sufficient protection for the contents. Where a moistureproof liner, such as of rubber, is used, it is not necessary that the container also be moistureproof or prevent the escape of vapor, and it may in this case consist of a paper carton of well known form and construction. Where the container is of metal or other moistureproof material, the liner may be omitted.

The container may be of any material or construction possessing suitable structural strength 55 and a high degree of moistureproofness. It may consist of two or more elements giving these characteristics in combination such as a stiff, supporting member with a moistureproof lining, or the container walls may be coated or impregnated to give moistureproofness and a suitable moistureproof closure provided. The trays may be molded, stamped or otherwise shaped from paper products suitably impregnated or coated, from 60 sheet metals, from plastics, or in fact from any

material which is suitably resistant to solutions and waterproof.

The solution used may contain glycerol or other hygroscopic substance, preservatives, or in fact 5 be of any type suitable for maintaining the bands in proper condition for application as secondary closures.

While the invention has been described in terms of a hermetically sealed container employing trays, it is also contemplated to substitute for the trays water-tight compartments or pockets, each holding a single layer of vertically stacked bands so that the container as a whole will not have to be maintained in a given vertical position in order to maintain a given amount of solution 10 associated with each group of bands. 15

This type of package may be used for the storage and shipment of shrinkable bottle bands and bottle caps or other pellicular structures of regenerated cellulose, cellulose esters or ethers, 20 gelatin, casein and the like.

By the use of this invention, certain economies 25 are effected in the storage and shipment of hydrated, cellulosic structures and certain outstanding advantages over previous packaging are obtained. It is possible by means of this invention to greatly reduce the amount of liquid required in the package which results not only in a saving of the cost of the solution, but makes possible the use of a lighter container of less sturdy construction. Such containers are more readily handled 30 at a saving of both cost and labor.

These pellicular structures are customarily packed in a relative position and grouping which facilitates their subsequent application as bottle 35 closures and this arrangement in the container must be maintained throughout the ordinary hazards of shipping and handling the package, and also during the removal of the contents. This is greatly facilitated by the trays which serve to 40 support and hold the structures in position. Furthermore, if it be desired to send out a container which is not completely filled with bands, the remaining space in the container may be 45 filled with one or more trays which prevent the bands present from becoming disarranged.

In previous practice it has been found necessary, upon filling a can with bands which are to be completely immersed in solution, to leave a certain dead space at the top of the can which 50 amounts to about 10% of the total volume so that solution may be added and allowed slowly to trickle down through the bands. By the use of the process of the proposed invention, this dead space is no longer required and the effective 55 capacity of the container is thereby increased.

If the removal of the bands from the container extends over a considerable period of time, the bands of the lower layers are protected from 60 drying out by the trays acting as separators during the period that the upper layers of bands are removed.

Where the expression "hollow pellicles" is used in the specification and/or claims, it is intended 65 to be generic to bands, and to other similar hollow bodies.

Since it is obvious that many changes and modifications of the invention can be made within the nature and spirit thereof, it is to be understood that the invention is not to be limited thereto except as set forth in the appended claims.

I claim:

1. A package comprising a moistureproof container and a plurality of superimposed flat bot- 75

5 tomed trays therein, said trays containing hollow shrinkable hydrated gel pellicles and a moistening solution therefor, said moistening solution containing a softner for the pellicle, the said pellicles being partially immersed in said solution and upright with a bottom portion resting on the tray bottom whereby said pellicles are kept in an unimpaired moist gel condition.

2. The package of claim 1 when the moisture-
10 proof container is a rubber bag which is enclosed in an outer casing and the pellicles are from the

group consisting of regenerated cellulose, cellulose esters, cellulose ethers, gelatin and casein.

3. The package of claim 1 when the pellicles are from the group consisting of regenerated cellulose, cellulose esters, cellulose ethers, gelatin and casein, and when the pellicles project above the rim of the tray. 5

4. The package of claim 1 when the pellicles are regenerated cellulose and the softner solution contains glycerin. 10
